UNITED STATES PATENT OFFICE.

ALFRED EDWIN BRAY, OF LUBERTZY, RUSSIA.

FUEL-SUPPLY REGULATOR FOR INTERNAL-COMBUSTION ENGINES.

1,080,887.

Specification of Letters Patent.

Patented Dec. 9, 1913.

Application filed January 21, 1911. Serial No. 603,841.

To all whom it may concern:

Be it known that I, ALFRED EDWIN BRAY, a subject of the King of Great Britain, and a resident of the station Lubertzy of Moscow-Kasan Railway, Russia, engineer, have invented new and useful Improvements in Fuel-Supply Regulators for Internal-Combustion Engines, of which the following is a specification.

10 My invention has for its object a novel mechanism for regulating the fuel supply of internal combustion engines. Such mechanism is shown in the annexed drawing, in which—

15 Figure 1 is a side view and Fig. 2 a front view of the mechanism; Fig. 3 is a longitudinal section of the fuel pump and Fig. 4 partly a longitudinal section and partly a side view of the regulating device.

20 On the distributing shaft S of the engine two cams 1 are mounted, in engagement with rollers 16, loosely mounted on a pivot passing through the pin end of a lever 2, having its fulcrum at 2' on the engine frame. When the shaft S rotates, the cams 1, by means of the rollers 16 raise the lever 2 in the direction of the arrow C (Fig. 2). The cams 1 are held in engagement with the rollers 16 by the weight of the lever 2 and the rollers. On lever 2 is also mounted by means of a pivot 3 a bracket 4, having two plates 5, 6, fastened to it. The bracket 4 is also provided with a rear projection 3' connected by means of a helical spring 7 with a stationary projection 3'', extending from a depending lug 4' of the lever 2. The spring 7 tends to turn the bracket 4 in the direction of the arrow A (Fig. 2). The piston rod 9 of the fuel pump 10 is provided on its lower end with a block 8, being cut away at 8' and provided with a curvilinear surface 8''. From the block 8 projects an extension 38 entering a guiding slot 39 in the engine frame.

45 In the normal position of the parts, plate 6 on the bracket 4 bears with its upper end against the cut-away part 8' of the block 8 and lies in a recess formed between the cut-away part 8' and the curved surface 8''. When the lever 2 is raised in the direction of the arrow C (Fig. 2), the upper end of the plate 6 is forced against the block 8 on the lower end of the piston rod 9, thereby pushing the latter and the piston attached thereto in the cylinder

10 upward, at the same time compressing the spring 22' inside the cylinder (Fig. 3), feeding liquid fuel to the mixing chamber of the engine. The return stroke of the pump piston is effected by the spring 22'. 60

Now, I will describe the device for regulating the supply of the liquid fuel to the engine. On a rotary spindle 23', arranged parallel with the shaft S, is mounted a hollow cone 11, in such a way that it will rotate 65 with the spindle, but can move along the latter. The spindle 23' is rotated from the shaft S by means of the gears 23, 24. The gear 23 is secured to the spindle 23', and provided with an elongated hub 23. On the inner end of said hub weights 26 are mounted on pivots 25, which weights on the rotation of the spindle 23', owing to centrifugal force, swing outward and exert on the cone 11 a pressure, which pressure increases with 70 the increase in the number of revolutions of the spindle 23'. Against the hub of the cone 11 bears a collar 21' loosely surrounding the spindle 23' and provided with two pivot pins 27 which are engaged by two 75 links 12, which, in turn, are pivotally connected with a lever 13, rigidly secured to an idler shaft 14, adapted to freely revolve in the engine frame. Rigidly secured to the same shaft 14 is a lever 15, provided at its 80 lower end with a slot or shoulder, adapted to be engaged by the upper edge of the plate 5 on bracket 4. A helical spring 17 bearing at one end against an adjustable nut 21 on spindle 23' and at its other end against the 85 said collar 21', is wound around a reduced portion of spindle 23', and has for its purpose to shift the cone 11 back to its normal position on the spindle, as its rotation ceases. 90

In testing the engine, the parts are so adjusted that when the engine runs at ordinary speed the slot or shoulder provided on the lower end of the lever 15 is not in the path of the plate 5 on the bracket 4, whereas even upon a slight increase in the number of revolutions the lever 15 is moved into the path of the plate 5. 95

The operation of my new regulating device is as follows: Upon an increase in the 100 number of revolutions of the engine shaft S above the normal, the cone 11 is moved by the weights 26 toward the right in Fig. 1, whereby the lever 15 is moved into the path of the plate 5 on bracket 4. When in 105

55 the piston attached thereto in the cylinder

this position of the parts the lever 2 is lifted by means of the cams 1 and rollers 16, the plate 5 will strike against the lower end of lever 15. Thereby the bracket 4 is swung about its pivot 3 in a direction opposite to the direction marked by the arrow A in Fig. 2. Consequently the plate 6 on bracket 4 will pass by the recess in the block 8 and the pump rod 9 will remain in inoperative position, so that the pump 10 will not supply any fuel to the engine. As the number of revolutions of the engine is thereby decreased to normal, the cone 11 will be moved back to its original position by the spring 17, and by means of lever 12, connected with the cone 11, the lever 15 will again be moved out of the paths of the plate 5, so that on the next upward movement of lever 2 the plate 6 on bracket 4 will engage the recess in block 8, forcing the piston rod 9 upwardly in cylinder 10, thereby operating the fuel pump. The time when the cone 11 shall operate can be easily determined by the tension of the spring 17, which can be regulated by the adjustable nut 21 on spindle 23'. The stroke of the piston of the fuel pump 10 can also be regulated by hand so as to increase or reduce the quantity of the fuel supplied with each stroke of the piston. This is effected by the aid of a knurled nut 18, which may be easily screwed up and down on the lower end of a cylinder 10 by hand whereby the extent of movement of the piston rod 9 and thus the stroke of the piston in the cylinder 10 can be increased or decreased at will. The nut 18 can be secured in position by a lock-nut 19 (Figs. 2 and 3). This regulation is resorted to when the engine is intended to work with a constant load for a long period. In order to stop the engine, the rollers 16 after studs 20 have been removed are moved to the positions shown in dotted lines and are held in said positions by said studs 20 which are put back into their places. In this position of the rollers, the cams 1 cannot contact therewith. Of course, one cam and one roller are sufficient for operating the fuel supply. The reason that two cams and two rollers are provided is to enable one to supply with one pump fuel twice in the course of one revolution.

What I claim is:—

1. In a device for regulating the fuel supply of internal combustion engines, the combination with the fuel pump, a piston rod therefor, and a distributing shaft of the engine, of a cam rotating therewith, a rotary spindle adapted to be rotated by said distributing shaft, a lever pivoted to the frame of the engine, adapted to be engaged by said cam, a bracket pivoted to said lever, two plates fastened to said bracket, one of said plates adapted to engage the piston rod of the fuel pump, a stop arranged to be moved

into the path of the other plate to prevent the first mentioned plate from engaging the piston rod, a hollow cone rotatably connected with said rotary spindle, but adapted to move axially thereon, weights pivoted to said cone and adapted to move the same lengthwise on said rotary spindle, a spring arranged to resist said movement and means connecting said hollow cone and said stop and adapted to move said stop into the path of said plate upon a predetermined increase of the speed of rotation of said rotary spindle above normal. 70

2. In a device for regulating the fuel supply of internal combustion engines, the combination with the fuel pump, a piston rod therefor, and a distributing shaft of the engine, of a cam rotating therewith, a rotary spindle, adapted to be rotated by said distributing shaft, a lever pivoted to the frame of the engine, means on said lever adapted to be engaged by said cam to lift said lever about its pivot, a bracket pivoted to said lever, two plates fastened to said bracket, one of said plates adapted to engage the piston rod of the fuel pump, a stop arranged to be moved into the path of the other plate to prevent the first mentioned plate from engaging the piston rod, a hollow cone rotatably connected with said rotary spindle, but adapted to move axially thereon, weights pivoted to said cone and adapted to move the same lengthwise on said rotary spindle, a spring arranged to resist said movement and means connecting said hollow cone and said stop and adapted to move said stop into the path of said plate upon a predetermined increase of the speed of rotation of said rotary spindle above normal, and an adjustable nut on said rotary spindle for regulating the tension of said spring, thereby determining the period of shutting off the fuel supply. 95

3. In a device for regulating the fuel supply of internal combustion engines, the combination with the fuel pump, a piston rod therefor, and a distributing shaft of the engine, of a cam rotating therewith, a rotary spindle adapted to be rotated by said distributing shaft, a lever pivoted to the frame of the engine, means on said lever adapted to be engaged by said cam to lift said lever about its pivot, a bracket pivoted to said lever, two plates fastened to said bracket, one of said plates adapted to engage the piston rod of the fuel pump, a stop arranged to be moved into the path of the other plate to prevent the first mentioned plate from engaging the piston rod, a hollow cone rotatably connected with said rotary spindle, but adapted to move axially thereon, weights pivoted to said cone and adapted to move the same lengthwise on said rotary spindle, a spring arranged to resist said movement and means connecting 110

said hollow cone and said stop and adapted to move said stop into the path of said plate upon a predetermined increase of the speed of rotation of said rotary spindle 5 above normal, and a nut at the lower end of the pump cylinder for varying the stroke of the piston of the fuel pump.

In testimony whereof, I have signed my name to this specification in the presence of two subscribing witnesses.

ALFRED EDWIN BRAY.
